UNITED STATES PATENT OFFICE.

ALBERT M. BALLARD, OF YALE, OKLAHOMA, ASSIGNOR TO SUN OIL COMPANY, OF PHILADELPHIA, PENNSYLVANIA, A CORPORATION OF NEW JERSEY.

OIL AND GAS SEPARATOR.

Application filed March 16, 1922. Serial No. 544,301.

To all whom it may concern:

Be it known that I, ALBERT M. BALLARD, a citizen of the United States, residing at Yale, county of Payne, and State of Oklahoma, have invented a new and useful Improvement in Oil and Gas Separators, of which the following is a full, clear, and exact description, reference being had to the accompanying drawings, which form a part 10 of this specification.

My invention relates to apparatus for separating oil and gas direct from wells. An example of such an apparatus is set forth in the Ballard Patent No. 1,327,691, 15 January 13, 1920.

This apparatus comprises a tank having an oil and gas inlet, a valved gas outlet near the top, a valved oil outlet near the bottom, a float connected with both valves and 20 adapted, as the oil level rises, to close the gas valve and open the oil valve, and as the oil level sinks, to close the oil valve and open the gas valve. The float may be connected with but one of the valves, the other 25 valve being automatic, manually operable or it may be omitted. The float is guided centrally along a vertically extending rod and carries an arm which engages a second vertically extending guide rod having lateral 30 extensions secured to the first guide rod, thereby tending to hold the float from rotating or turning.

The object of the present invention is to improve the structure for guiding the float 35 in its vertical movement so as to increase its stability and with more certainty prevent it from turning, and also prevent direct sliding contact between the wall of the tube in the float and consequent wear and premature destruction.

A preferred embodiment of the invention is shown in the accompanying drawings, in which—

Fig. 1 is an elevation of the tank partly 45 broken away to disclose the interior float mechanism.

Fig. 2 is an enlarged elevation, partly in section, of the float.

Fig. 3 is a detail sectional view of one of 50 the end bearings of the float.

The flow tank *a* is provided with pipes *b* for admission of gas and oil, oil outlet pipes *c* leading to the stock tanks and gas outlet pipes *d* leading to the compressor.

Extending across the tank are cross bars

e and *f* between which are supported a central vertically extending guide rod *g* and two side guide rods *h*, *h*.

A float *i* is movable vertically on the guide rods and is connected, by links *k* and levers *l*, with valves *m* on the oil outlet pipes *c*.

Extending through the vertical center line of the float is a tube *o*, which is of somewhat greater diameter than the central guide rod *g*. Arms *n*, *n*, on opposite sides of the float 65 slidably engage the side guide rods *h*, *h*.

The tube *o* is somewhat longer than the float *i* is high, the ends of the tubes projecting respectively above and below the float. Each projecting end is threaded for the re- 70

ception of a cap or bearing *p*, either plain or bushed, which slidably engages the guide rod *g*. This bearing may have a sliding fit on the guide rod *g* and at any rate is of smaller diameter than the tube *o*, so that it 75 absorbs all the wear arising from the travel of the float upon the guide rod *g*. This keeps the rod *g* from contacting with the tube *o*, preventing wear upon the tube. Such wear soon produces leakage and destroys the 80 function and use of the float.

By supporting the side guide rod or rods *h* independently of the central guide rod *g*, the float cannot turn on its axis. If the side 85 guide rod or rods *h* were secured direct to the central guide rod *g*, as by a set screw, any loosening of the connection would permit the side guide rod to bodily turn about the central guide rod as an axis, thereby preventing it from functioning in the in- 90 tended manner. Moreover, in such a construction, if the central guide rod were not firmly anchored at top and bottom, it could turn on its own axis. In either case a movement of rotation of the float would not be 95 prevented.

By the improvements above described the float is effectually prevented from turning, excessive wear and tear are avoided, and no strain is imposed upon the connections between the float and the valves controlling 100 the oil outlets.

As the gas and oil enter the tank, the gas fills the tank and flows out the gas outlet *d*. The level of the oil rises, lifting the float, 105 thereby opening the valves *m* on the oil line. This allows the oil to flow into the stock tanks. As the oil recedes, the float falls, thereby moving the valves *m* toward their closed positions. The cross bars *e* and *f* 110

limit the up and down movement of the float.

Having now fully described my invention, what I claim and desire to protect by
5 Letters Patent is:

1. In an oil and gas separator, the combination with the tank, of a fluid outlet control float within the tank, a tube extending vertically through the float and projecting
10 beyond the ends thereof, a vertically extending rod of substantially smaller diameter than the tube and upon which the float is vertically guided, and annular flanged bearings secured to the ends of the tube and on
15 the other periphery thereof, the internal diameter of the flanges forming bearings and being less than that of the tube so that

the sliding contact will be between the guide rod and the flanges, thereby avoiding wear and tear upon the tube.

20

2. A float for an oil and gas separator, having a tube extending therethrough, said tube being connected to the float and having threaded ends extending beyond the float, and float guide rod members engaging said threaded ends having openings, guide rod openings therethrough concentric with the tube and of a smaller diameter than the opening through the tube.

25

In testimony of which invention, I have
hereunto set my hand, at Toledo, Ohio, on
this 11 day of March, 1922.

ALBERT M. BALLARD.
